(57) **CLAIM**

The ornamental design for a packaging container, as shown.

DESCRIPTION

FIG. 1 is a perspective view of a packaging container from a first side in a partially open state;

FIG. 2 is a perspective view thereof, from the first side, in a closed state;

FIG. 3 is a perspective view thereof, from a second side, in a closed state;

FIG. 4 is a plan view of an exterior thereof, in an open state;

FIG. 5 is a plan view of an interior thereof, in an open state;

FIG. 6 is a perspective view of an interior thereof, in an open state; and,

FIG. 7 is a perspective view of an exterior thereof, in an open state.

The broken lines in the figures represent perforations in the container, for separating portions of the container.
